RECLINING CHAIR

Joseph M. Jensen, Oakland, Calif., assignor to
 Amanda Jensen, Oakland, Calif.; C. Stanley
 Wood, executor of said Amanda Jensen, de-
 ceased

Application May 19, 1945, Serial No. 594,677

4 Claims. (Cl. 155—45)

1

My present invention relates to chair-type furniture and more particularly to an improvement in reclining chairs by which the seat and back portions of the chair may be adjusted and supported in various positions with respect to each other.

An object of my invention is to provide a reclining chair in which the seat and back forming portions of the chair may be positioned relative to each other in a new and novel manner and without the use of ratchets, racks, or like mechanisms.

Another object of the invention is to provide an improved hinge for the association of two relatively movable members which will permit the hinging of said members between an inclined right angle relation and a flat coplanar relation.

Another object of the invention is to provide a chair having hingedly mounted seat and back portions and a novel form of spring by which the operation of the hinged parts is improved in a novel and effective manner.

A further object of the invention is to provide a combined support for the swinging back and seat portions of a reclining chair, in which the relative positions of the back and seat of the chair will be determined by the forces exerted thereupon by the distributed weight of an occupant without other adjusting or positioning means.

Another object of the invention is to provide a pivot-like support for the back and seat portions of reclining chair, in which the pivot point about which the parts move will form a fulcrum over which the distributed weight of an occupant may be balanced to thereby position the back and seat portions of the chair in conformity with the posture assumed by an occupant.

Other objects and advantages will be in part evident to those skilled in the art and in part pointed out hereinafter in connection with the accompanying drawing, wherein there is shown by way of illustration and not of limitation a preferred embodiment of the invention.

In the drawing:

Figure 1 is a sectional side elevation taken in a plane immediately adjacent the inside of the near side of a chair constructed in accordance with the invention.

Figure 2 is a view similar to Figure 1 of the drawing, showing the parts of the chair in another position, or as viewed along line II—II of Figure 3, and

Figure 3 is a reduced bottom view of the chair as shown in Figure 2 of the drawing.

2

Reference is now made to Figure 1 of the drawing, where I have shown the invention in its simplest form. In this showing the chair body is illustrated as comprising two vertically disposed and spaced side members 10, that are held in spaced relation by a transversely extending front member 11 and a similarly disposed rear member 12. The front and rear members 11 and 12 operate to maintain the sides 10 of the chair in parallel spaced relation and serve certain other functions as will hereinafter appear. It will be understood that the chair may take many other forms; for example, it may be of the overstuffed type, in which the sides and ends will be completely enclosed by upholstery, or it may be of metal with a modernistic design, or constructed of rattan or willow. The only requirement will be that the chair frame be adapted to provide a pivotal support, designated by the numeral 13 in the drawing, upon which a back portion 14 may be pivotally mounted to swing from a substantially vertical position to a horizontal position. In addition to this, the transversely disposed front member 11 should be arranged to operate as a support for a floating bottom or seat portion of the chair, designated by the numeral 15.

As here shown, the back and seat portions 14 and 15 of my improved chair are provided respectively with tufted cushions 16 and 17, that are preferably held in place by any suitable means when applied to the chair. In this arrangement the back portion 14 of the chair is provided with a pair of forwardly extending brackets 18, one at each side thereof at its lower end. Likewise the floating seat portion 15 of the chair is provided with a pair of upwardly extending brackets or hinge forming members 19, one at each side and near its inner end. These bracket members 18 and 19 are pivotally secured together as at 20 and provide a hinged connection between the back portion 14 and seat portion 15 of the chair. In this manner the back and seat portions 14 and 15 are supported in whole or in part and operate with respect to the pivot 20 as an articulated unit. As an additional element, the back portion 14 of the chair has a downwardly depending stop engaging member 21 that is adapted to cooperate with a resilient spring stop 22 shown in the form of a leaf spring which is carried by the transversely extending rear member 12 of the chair. When the back portion 14 of the chair is in its upright position as here shown, it will be seen that the pivotal connection 20 between the bracket members 18 and 19 will form a support

for the inner end of the seat portion 15. At the same time the outer end of the seat portion 15 of the chair will be slidably supported by the transversely extending front member 11 of the chair.

In order to counterbalance the weight of the back portion with its pad 16 and normally return the chair to its conventional position, the front portion 11 of the chair is shown as carrying a spring means 23, which is so connected at its outer end to the seat portion 15 that it will permit of a slight forward and backward sliding movement of the seat portion of the chair. This spring means 23 operates to exert a downward pull adjacent the inner end of the seat portion 15, which will be transmitted to the brackets 18 and thus the back and seat portions 14 and 15 of the chair will be caused to normally assume the position in which they are here illustrated. This spring means 23 is here shown as comprised of leaf spring units, each of which have a long leaf 24 with a reversed curvature and an upper leaf 25 of proper curvature which will cooperate with leaf 24 to produce the desired downward exertion of force by the spring 23. As shown, the chair is preferably provided with two leaf springs 23, each of which extends inwardly from the front portion 11 and over a strap 26 that is attached to the bottom of the seat portion 15. This will permit the seat portion 15 of the chair to move relative to the spring 23 from one of its extreme positions to the other without materially affecting the downward pull exerted thereby.

Upon referring to Figure 2 of the drawing, it will be noted that when the back portion 14 is swung back into its horizontal position, the bracket forming members 18 and 19 will extend upwardly beyond the pivotal point 13, and as a result the seat forming portion 15 of the chair will be caused to rise and align itself in coplanar relation with the back forming portion 14. This will cause the tufted pads 16 and 17 to be also positioned in coplanar relation and thus provide a level surface upon which an occupant may lie perfectly flat. When the back portion 14 and the seat portion 15 are in this position, the stop engaging member 21 carried by the back portion 14 will swing upwardly and into engagement with the under side of seat forming portion 15 where it will operate to further insure a substantially coplanar alignment of the back and seat forming portions of the chair. During this operation the spring leaves 24 and 25 of the spring means 23 will be raised and placed under a greater stress, which will compensate for the over balancing weight of the back portion 14 when in this position. It will also be noted that the spring stop 22 has now moved outwardly so as to assume its normal inoperative position. At this point it will be noted that the rear member 12 of the chair frame is not extended up to a point where it is directly engaged by the back portion 14, and therefore the back portion 14 is provided with a cleat-like extension 28 which is positioned to engage the rear member 12 of the chair frame and thus support the back portion 14 in a horizontal position.

By referring to Figure 3 of the drawing, it will be noted that the stop engaging member 21 may be in the form of a simple panel-like extension secured to the back portion 14 where it will cooperate with the single spring means 22 positioned centrally with the back member 12 of the chair. In this figure the strap member 26 is shown as extending substantially across the bot-

tom of seat portion 15 and as secured thereto at its ends by means of adjustable screws 27, but it will be understood that the spring means 23 may be attached to the seat portion in other ways. It will be also evident that a single spring means 23 may be used if desired.

It is believed that the operation of my invention will be fully understood from the above. However, it should be explained that the details of construction may vary as the design and type of chair or the nature of its use may dictate. The principal point to be observed in the construction of a chair in accordance with this invention is that the hinged connecting point 20 provided by the brackets 18 and 19 carried respectively by the back portion 14 and the seat portion 15 should be located forwardly of the pivotal point 13 about which the back of the chair pivots, where the hinge point 20 will move in a substantially vertical arc located forward of the pivotal point 13. With the parts thus assembled, it will be seen that when an occupant is seated in the chair, his principal weight will be exerted downwardly and upon the seat portion 15. As a result, a leverage will be exerted through the bracket 18 about pivotal point 13, which will cause the back portion 14 to assume and maintain a substantially vertical position. Now should the occupant desire to recline, he can determine his final reclining position by merely dividing the weight exerted by his shoulders and buttocks, respectively, upon the back and seat portions of the chair, so as to balance these forces over the pivotal point 13 as a fulcrum at the point desired. This is explained by the fact that when the occupant exerts a backward force upon the back portion 14 with his shoulders, this effort will transfer some of the occupant's weight from the inner end of seat portion 15 and permit it to rise. During this operation some force may be exerted on the seat portion 15 by the legs of the occupant immediately above and under the knees, but this force will have no influence upon the operation above described. By the same token when the occupant desires to lie preferably flat he may distribute his weight between his shoulders and legs so as to remove more weight from the inner end of the seat portion 15. This will permit seat portion 15 to rise until the back and seat portions 14 and 15 of the chair assume positions in substantially level coplanar relation with each other.

While I have, for the sake of clearness and in order to disclose the invention so that the same can be readily understood, described and illustrated a specific device and arrangement, I desire to have it understood that the invention is not limited to the specific form disclosed, but may be embodied in other ways that will suggest themselves to persons skilled in the art. It is believed that this invention is new and it is desired to claim it so that all such changes as come within the scope of the appended claims are to be considered a part of this invention.

Having thus described my invention, what I claim and desire to secure by Letters Patent is:

1. A reclining chair comprising a frame having upstanding side portions, a back portion mounted between said side portions for movement about a transverse axis, a hinge means for supporting said back portion at a point rearwardly of said transverse axis and having an arm extending forwardly thereof, a floating seat portion hingedly connected with the arm of said hinge means

at a point forward of the said transverse axis, means for slidably supporting the outer end of said floating seat portion, and spring means tending to bias said floating seat portion downwardly at its hingedly connected end when said back portion is moved to its horizontal position, and a support at the rear end of said frame for limiting the backward movement of said hinged back portion to a horizontal position.

2. In a reclining chair of the character described, the combination of a frame having spaced side portions, a back forming portion pivotally connected at its lower end between said side portions and adapted to swing from a substantially vertical to a horizontal position, a floating seat portion pivotally connected at its inner end to the pivotally supported end of said back portion at a point forward of the latter's pivotal point and substantially above said seat portion, means for slidably supporting the free end of said seat portion, and leaf spring means carried by said frame adapted to bias said floating seat portion in a downward direction and yieldingly bias said back portion toward its substantially vertical position.

3. In a reclining chair of the character described, the combination of a supporting frame having spaced side portions and laterally extending front and rear portions, a back forming portion adapted to swing between said side portions from a substantially vertical to a horizontal position, a floating seat portion slidably mounted at its outer end upon the laterally extending front portion of said frame, a pair of brackets secured one at each side to said back forming portion near its lower end and pivotally engaging an adjacent side portion of said frame, a second pair of brackets secured one at each side near the inner end of said floating seat portion and hingedly connected at their ends to a corresponding one of said first brackets to form a hinged connection therebetween, said hinged connection being disposed to swing in a substantially vertical arc about and forwardly of the pivotal point about which said first brackets and said back portion move, spring means operating to exert a

downward force at the inner end of said floating seat portion, whereby said back portion will be normally held in a substantially vertical position, means carried by said back portion and extending downwardly below its pivotal point upon said frame, and spring means carried by the laterally extending rear portion of said frame adapted to cooperate with said downwardly extending portion and normally stop forward movement of said back portion as it approaches its substantially vertical position.

4. A reclining chair comprising: a frame; a chair seat fulcrumed at its forward end to the front end of said frame, said seat being arranged to support a relatively thick seat cushion; a chair back fulcrumed adjacent its lower end on the rear end of said frame and arranged to support a relatively thick back cushion; a forwardly extending hinge strap fastened to the lower end of said chair back; an upwardly extending hinge strap fastened to the rear end of said chair seat and hinged to said forwardly extending hinge strap at a point substantially forward of said chair back and substantially above the rear end 25 of said chair seat; and means associated with said frame and cooperating with said hinge straps for biasing said chair back to a substantially upright position.
